UNITED STATES PATENT OFFICE.

WALTER G. KING, OF NEW YORK, N. Y.

GOOGLES.

1,201,056.

Specification of Letters Patent. Patented Oct. 10, 1916.

Application filed December 16, 1915. Serial No. 67,124.

To all whom it may concern:

Be it known that I, WALTER G. KING, a citizen of the United States, residing at the city of New York, in the borough of Manhattan and State of New York, have invented certain new and useful Improvements in Goggles, of which the following is a full, clear, and exact description.

This invention relates to goggles which are used by automobilists and other persons desiring to protect the eyes from dust, dirt, and other foreign matter.

The object of the invention is to provide a goggle, the parts of which may be readily assembled, will maintain the transparent panes or lenses firmly in place, and yet permit these panes or lenses to be removed or replaced with the greatest ease and facility.

With this and other objects in view the invention consists in making each eye-piece of the goggle in separate sections, namely, a lens rim and an eye-cup, in providing a locking joint between these parts which will hold them against inadvertent separation, and in providing a part or parts carried by the eye-cup which are adapted to bear against the lens or transparent pane to firmly hold it within the lens rim after the eye-cup has been locked to the rim.

The character of the invention may also be understood by reference to the following description of an illustrated embodiment thereof shown in the accompanying drawings, wherein—

Figure 1 is a top view of a pair of goggles embodying the principles of the invention; Fig. 2 is a detail view of the lens rim; Fig. 3 is a detail view of the eye-cup, and Fig. 4 is a longitudinal section showing the construction by virtue of which the lens is held in position within the rim. Fig. 5 is a transverse section showing the same construction, and Fig. 6 is a detail showing the projecting lug on the eye or cap.

The goggles shown herein as embodying the invention comprise two eye-pieces 1 and 2, which may be connected by a chain 3 which serves as a bridge, although a rigid bridge may be used if desired. Each eye-piece consists of a lens-rim 4, preferably formed of sheet metal and consisting of a ring 5 having an inturned flange 6 which forms a seat for a lens or transparent pane 7 of any desired character.

The eye-cup is formed from a separate piece of sheet metal and is designated 8. It is of the usual shape and has the edge which bears against the face of the wearer protected by a padding or cushion 9 of leather or other suitable material. Straps or bands 10 of elastic material are secured to the eye-cups and are adapted to pass around the head of the wearer to hold the goggles in place. Ventilating openings 65 may be provided in the eye cup preferably by cutting U-shaped slits in the metal and by slightly offsetting the lips 12 which are thus formed. The cuts should be made so that the lips extend rearwardly to prevent 70 the passage of dirt or dust into the interior of the cup.

According to my invention the lens-rim and eye-cup are united by a locking joint which will hold the parts securely together 75 and will prevent their inadvertent separation, while permitting them to be separated at will when necessary. Various locking joints which will perform this function may be used. A bayonet joint has been found 80 suitable in practice and a specific embodiment of this type of joint will be described. Inwardly projecting protuberances 12 are formed upon the lens-rim by indenting the ring 5 adjacent its peripheral edge which is remote from the flange 6. The eye-cup is provided with a sleeve 13 of reduced diameter which is adapted to fit snugly 85 within the ring 5 and bayonet shaped grooves 14 are punched or otherwise formed 90 in this sleeve which are suitably spaced to engage with the protuberances 12. In order to prevent inadvertent rotation of the eye-cup relative to the lens-rim which might result in the separation of the parts, holes 95 or apertures 15 are formed at the inner ends of the bayonet grooves and the protuberances 12 fit into these apertures when the parts are properly assembled whereby the 100 protuberances will engage the walls of these apertures and prevent inadvertent rotation of these parts. If, however, a positive force is applied to cause a relative rotation of the lens and eye-cup, the sleeve will yield permitting the protuberance to again enter the 105 bayonet groove after which the parts may be easily separated.

The lens or transparent pane 7 which is mounted in the lens rim rests against the seat or flange 6 where it is firmly held in 110

place by lugs or fingers 16 which project from the peripheral edge of the sleeve 13. It may here be stated that the lens-rim and eye-cup are constructed from sheet aluminum or similar metals which will permit the fingers or lugs 16 to be easily bent and still possess the requisite stiffness to hold the lens or pane firmly against its seat. In assembling the parts these fingers or lugs are preferably bent slightly inwardly before the parts are assembled, and after the eye-cup and lens rim have been locked together the fingers or lugs are then pressed into engagement with the lens or glass to thereby force it against its seat. This instruction is also of importance because a bayonet or like joint between the eye-cup and lens rim does not permit of the axial adjustment of these parts; by making the lugs or fingers semi-flexible as described, these fingers may be bent into engagement with a lens of any desired thickness and hold it firmly in place within the lens rim. If it is necessary to remove the lens, the eye-cup or lens rim may be separated at will and the lens rim will then be free to be removed. It will therefore be seen that by the construction described the parts of the eye-piece including the lens may be readily assembled or disassembled, and yet when the parts are united each one is rigidly held in its correct position without any danger of inadvertently becoming loose or separating from the other parts.

I claim:

1. In a goggle construction, an eye-piece comprising a lens rim, a lens in said lens rim, a flange on said rim against which said lens is adapted to rest, an eye-cup, a locking joint between said lens rim and eye-cup, and a plurality of semi-flexible fingers carried by said eye-cup adapted to be bent to bear against said lens to hold it against its flange

when the eye-cup and lens rim are locked together.

2. In a goggle construction, an eye-piece 45 comprising a lens rim and an eye-cup, a lens in said rim, a flange on said rim against which said lens bears, a sleeve carried by the eye-cup adapted to fit into the lens rim, a locking joint between said sleeve and said lens rim, and a plurality of semi-flexible fingers carried by the eye-cup adapted to be bent to press against the lens to maintain it against its flange when the eye-cup is locked to the lens rim. 55

3. In a goggle construction, an eye-piece comprising a lens rim and an eye-cup, said lens rim having a flange, a lens in said rim resting against said flange, a sleeve on said eye-cup fitting into said rim, a bayonet joint between said sleeve and said lens rim, apertures in one of said parts forming a continuation of the bayonet grooves formed thereon, protuberances on the other part of the bayonet joint fitting into said apertures when the eye-cup is locked to the lens rim, and a plurality of fingers carried by the eye-cup adapted to bear against the lens and hold it in position against the flange when the eye-cup is locked to the lens rim. 60 70

4. In a goggle construction, an eye-piece comprising an eye-cup and a lens rim, a locking joint between these parts preventing axial adjustment thereof, a lens in said rim, and semi-flexible fingers carried by said eye-cup adapted to be bent into engagement with the lens and maintain it in position in the lens-rim. 75

In witness whereof, I subscribe my signature, in the presence of two witnesses.

WALTER G. KING.
